UNITED STATES PATENT OFFICE

99,863

DESIGN FOR A COSTUMER

North D. Hayes, Topeka, Kans.

Application February 24, 1936, Serial No. 61,333

Term of patent 14 years

To all whom it may concern:

Be it known that I, North D. Hayes, a citizen of the United States, residing at Topeka, in the county of Shawnee and State of Kansas, have invented a new, original, and ornamental Design for a Costumer, of which the following is a specification, reference being had to the accompanying drawing, forming part thereof.

The figure is a perspective view of a costumer, showing my new design.

I claim:—

The ornamental design for a costumer as shown.

NORTH D. HAYES.
